G. W. Earushaw

Attorney

UNITED STATES PATENT OFFICE.

ROBERT S. BUTLER, OF JOPLIN, MISSOURI.

RAIL CLAMP.

Application filed May 19, 1922. Serial No. 562,208.

To all whom it may concern:

Be it known that I, ROBERT S. BUTLER, a citizen of the United States, residing at Joplin, in the county of Jasper and State of Missouri, have invented certain new and useful Improvements in Rail Clamps, of which the following is a specification.

This invention relates to rail clamps, and more particularly to pneumatically controlled clamps adapted to engage a rail to clamp a digging machine, excavator, or the like in position.

In a copending application, Serial No. 416,175, filed October 11, 1920, I have disclosed and claimed a mine shovel consisting of a cylinder, a shovel connected thereto, the cylinder and shovel being mounted on a wheeled frame adapted to travel on a track, and in the present invention, I provide a clamp adapted to be secured to the frame in any suitable manner to retain it in position when the shovel is thrust forwardly into a pile of material, or to prevent the machine from overturning when a loaded dipper is elevated and extended.

An object of the invention is the provision of a pneumatically controlled clamp that may be quickly attached to the rail and released therefrom.

In the accompanying drawings, I have shown one embodiment of the invention. In this showing:

Figure 1 is a vertical sectional view of a rail clamp in position,

Figure 2 is a plan view,

Figure 3 is a horizontal sectional view on line 3—3 of Figure 1,

Figure 4 is a vertical sectional view on line 4—4 of Figure 1, and,

Figure 5 is a detail perspective view of the movable jaw of the clamp.

Referring to the drawings, the reference numeral 1 designates a cylinder having a suitable inlet opening 2 adapted to be connected to a source of supply by a pipe 3.

A depending arm 4 is cast with the cylinder and the upper end of this arm terminates in a hook 5, adapted to be arranged over a suitable support 6. The depending arm is substantially T-shaped in transverse cross-section, being provided with a flange 7. The lower end of the arm is offset laterally, as at 8, and is provided with a fixed jaw 9 having a recess 10 to engage the tread or ball of the rail. The upper and lower walls of this recess are parallel, as at 11, but are

arranged at an angle. This jaw is adapted to be arranged on one side of the tread or ball of a rail 12, as shown in Figures 1 and 2, and if desired, a suitable shim 13 may be arranged between the jaw and the outer side of the tread to prevent wear on the jaw, and to permit of a better hold on the rail. The shim is provided with offset ends 14, adapted to engage the sides of the jaw.

A movable jaw 16 is pivotally supported on the flange 7. As shown, a pin 17 passes through the flange and is adapted to be received in openings 18 in brackets 19 formed on the jaw. The face of this jaw is provided with a V-shaped recess 20, the upper and lower walls of which recess are parallel as at 21, and arranged at an angle. Links 22 are pivotally mounted on the opposite ends of a pin 23 extending through a boss 24, carried on the upper portion of the fixed jaw. The opposite ends of these links are connected to a link 25 by a pin 26. The link 25 is in turn connected to the movable jaw by a pin 27, received in openings 28 in the brackets 19. The ends of the pin 26 are connected to coil springs 29, having their upper ends secured in suitable supports 30, carried by the cylinder.

A piston 31 is mounted within the cylinder and is adapted to bear upon the connected ends of links 22 and 25 when fluid is admitted to the cylinder.

The operation of the device is as follows:

The clamp is supported on a bar or pin 6 by the hook 5 and the jaws are automatically arranged on opposite sides of the rail 12. Normally, the springs 29 exert an upward pull on the adjusted nut or link 25 to swing the movable jaw 16 on its pivot and disengage it from the rail. When fluid is admitted to the cylinder, forcing the piston down, the link 25 moves in the opposite direction against the tension of the spring, causing the jaws to engage the rail.

The use of a pneumatic rail clamp is advantageous in that it permits instant engagement and disengagement and saves a great deal of time formerly necessary in adjusting manually operated clamps. The center of gravity being to one side of the center of the hook causes the stationary jaw to automatically disengage from the rail, thus disengaging both jaws when pressure is relieved. The inclined faces of the jaws insure proper engagement with the ball of the rail when closing, should they happen

to be positioned slightly above or below the ball or proper level.

It is to be understood that the form of my invention herewith shown and described is to be taken as a preferred example of the same, and that various changes in the shape, size, and arrangement of parts may be resorted to without departing from the spirit of the invention or the scope of the subjoined claims.

Having thus described my invention, I claim:

1. A rail clamp comprising a cylinder, an arm extending therefrom, a fixed jaw carried by said arm, a movable jaw pivoted thereon, a piston in said cylinder adapted to force said movable jaw to locked position, and means for normally maintaining said movable jaw in open position.

2. A rail clamp comprising a cylinder, an arm extending therefrom, a fixed jaw carried by said arm, a movable jaw pivoted thereon, a piston in said cylinder adapted to force said movable jaw to locked position, and a spring operatively connected to said movable jaw to normally maintain it in open position.

3. A rail clamp comprising a cylinder, an arm extending therefrom, a fixed jaw carried by said arm, a movable jaw pivoted thereon, a link pivoted on said arm and connected to said movable jaw, a piston in said cylinder adapted to engage said link when in lowered position to retain said movable jaw in closed position, and means for nor-

mally maintaining said movable jaw in open position.

4. A rail clamp comprising a cylinder, an arm extending therefrom, a fixed jaw carried by said arm, a movable jaw pivoted thereon, a link pivoted on said arm and connected to said movable jaw, a piston in said cylinder adapted to engage said link when in lowered position to retain said movable jaw in closed position, and a spring operatively connected to said link to normally maintain said movable jaw in open position.

5. A rail clamp comprising a cylinder, an arm extending therefrom, a fixed jaw carried by said arm, a movable jaw pivoted thereon, a link pivoted on said arm and connected to said movable jaw, a piston in said cylinder adapted to engage said link when in lowered position to retain said movable jaw in closed position, and a hook formed on said web and adapted to engage a suitable support.

6. A rail clamp comprising a cylinder, an arm extending therefrom, a fixed jaw carried by said arm, a movable jaw pivoted thereon, and a piston in said cylinder adapted to force said movable jaw to locked position.

In testimony whereof, I affix my signature in presence of two witnesses.

ROBERT S. BUTLER.
